UNITED STATES PATENT OFFICE.

EDWIN R. GILL, OF YONKERS, NEW YORK, ASSIGNEE, BY MESNE ASSIGNMENTS, TO
HALL SWITCH & SIGNAL COMPANY, A CORPORATION OF MAINE.

SELECTIVE MECHANICAL OPERATOR.

1,105,194.

Specification of Letters Patent. Patented July 28, 1914.

Application filed May 25, 1905. Serial No. 262,185.

To all whom it may concern:

Be it known that I, EDWIN R. GILL, a citizen of the United States, residing in the city of Yonkers, county of Westchester, and State of New York, have invented a certain new and useful Improvement in Selective Mechanical Operators, of which the following is a specification.

This invention relates to means whereby 10 a machine element, such as a wheel or other mechanical device, may be indirectly brought into a predetermined position for any desired purpose.

The invention is applicable to the operation 15 of combination locks, the sending of signals, ringing of bells, firing of explosives and like uses.

This invention is particularly useful in its preferred forms for employment in connection 20 with telephonic and telegraphic systems. It can be operated by hand or electrically, and, in the latter case, an indefinite number of similar instruments can be placed on the same circuit and they can each be operated by a key at any point on such circuit without interfering with the others.

As will be developed hereinafter, I aim to provide an apparatus in which an element, such as a wheel, may be actuated by impulse 30 means in such a way that it may be progressively stepped by each one of a codally arranged series of impulses of different characteristics, and so that if an impulse of a given character is made out of its proper 35 code relation the stepping will be interrupted, and the wheel returned to normal.

Although I have specifically illustrated herein a preferred form which is particularly well adapted for telegraphic use, it is 40 to be understood that this invention is not limited to such use and that in certain embodiments it may be operated by any other desired agency, as well as by electricity. With this understanding, I shall first describe 45 the specific form in question with certain modifications illustrated in detail, and shall then explain the advantages of the invention embodied therein, noting certain further forms which my broad invention 50 may take.

In the accompanying drawings, Figure 1 shows a selective telegraphic signal embodying my invention, said figure being a side elevation thereof with a portion of the supporting framework removed to permit fuller

illustration; Fig. 2 is a plan view of the same with the magnet removed; Fig. 3 is an end elevation of the same; Figs. 4 and 5 are detail views illustrating the preferred operation of the drop; Figs. 6, 7 and 8 are detail perspective views illustrating the retaining and releasing mechanism in three different positions, Fig. 9 is a diagram of circuits preferably employed with this form of my invention; and Fig. 10 is a side view of 65 certain details.

The main essential of this invention is a machine element intended to be brought to a predetermined position, whatever the form, substance or mode of movement of said machine element and whatever end is subserved thereby. In the preferred form about to be described, this machine element is a toothed sector embracing any suitable arc, whether a complete circle, as shown or not; and in 70 my claims the word "sector" is intended to include a complete wheel and it is one of the novel features of the embodiment shown that means for moving such a wheel or sector by uniform steps are combined with 75 means for turning the wheel or sector backward to a normal starting point at proper times. The importance of this feature of the invention will appear hereinafter.

The selective telegraphic call or signal 80 herein specifically shown and described is mounted upon a base 1, carrying four terminals or binding posts 2, 3, 4 and 5 at the four corners of the working parts. The main operating magnet 6 is mounted on said 85 base together with the selective mechanism carried by the metallic framework 7. The magnet operates through a long swinging armature 8, secured preferably to the top of the magnet by the spring 9, and swinging 90 opposite the lower pole-piece 10. The bowed spring 11 engages with the abutment 12, tending continuously to throw the armature outward as in Fig. 1.

The machine element to be operated takes 100 the form of a toothed wheel 13, mounted on the shaft 14 and supplied with a returning device in the form of a spring 15 which tends always to return the wheel to the normal starting point, approximately as shown in 105 Fig. 1. With the mainwheel 13 there moves an arm 16, carrying a pin 17 and when, by proper manipulation, the wheel has been turned forward in a clockwise direction, as shown in Fig. 1, said pin lifts the wire arm 110

18 which, by turning the shaft 19 and lifting the wire arm 20, releases the drop 21 from the retaining hook 22 on said arm 20 (see Figs. 1, 2 and 3). This operation of 5 the drop preferably rings a bell as herein-after described, but any other signal operated by proper movement of the pin 17 would be within this branch of my invention.

10 The instrument which directly impels the main wheel is the main pawl 23 which depends from a pivotal support on the long lever 24, pivoted at 25, which pawl is held toward the main wheel as by the spring 26 15 on said lever. At the same time the wire arm 27 prevents said spring from pushing the pawl too far over. The main operating lever 24, is raised by a long depending spring arm, 28, the lower end of which impinges constantly against the surface of the armature 8. Thus in the form shown (which is not obligatory) the operation of the main wheel is accomplished by the mere weight of the lever 24 and attached parts, 20 the armature 8 and spring 11 serving to raise said lever preparatory to a renewed operation. Between successive operations of the pawl 23, the main wheel or sector is held normally in place against the tendency 25 of the spring 15 by proper retaining means, which in the drawings takes the form of the pawl 29 pivoted at 30 so that its outer tip falls by gravity or otherwise behind successive teeth on the wheel 13 as they pass 30 under it.

The means so far described are obviously sufficient for rotating the wheel 13 manually or electrically so as to operate the drop 21. In order, however, that this may be accomplished selectively the following agencies are 40 preferably employed. The total apparatus about to be described is used for production of what may be called a "free" selective system, whereby is meant one wherein any 45 possible combination of long and short movements or pauses within the limits of the instrument may be employed on a system of mutually connected instruments without any danger whatever of the wrong 50 instrument being operated, and I have found that, by properly combining the elements a device can be made which permits of selective operation of any one of a number of wheels by the use of any desired combination. Where this means is used there 55 is no necessity for comparing the combinations among themselves and contriving to prevent mutual interference. Consequently the number of instruments which can be 60 operated successfully on a single circuit is comparatively very great.

In producing a selective system, as above outlined, it is necessary to supply dis-engaging mechanism whereby the retaining means 65 is made to release the main wheel so that it

will automatically return to its starting position, and to combine therewith a restoring device, or means whereby the effect of said dis-engaging device is counteracted or interfered with at the proper time.

70 Referring now to Figs. 1, 2, 3, 6, 7, 8 and 10 it will be seen that my preferred device is provided with a series of pins 45 projecting from one face of the wheel 13 near the bases of certain of its teeth. These form 75 the disengaging means, operation of which is best understood by inspection of Figs. 6, 7, 8 and 10. As there shown, the pawl 29 is provided with a side extension providing a bent raising finger 46 and a supporting 80 lip 47. The latter forms a right angle bend within which hang two gravity hooks 48 and 49 pivoted near the top of the frame as at 50, and 51, and tending, by virtue of the balance weights 52, 53 to fall under the lip 85 47 when it is raised. The downwardly bent tip on the pawl finger 46 is so placed that as each pin 45 passes under said finger, on movement of the wheel 13, the pawl is raised out of the path of the teeth on said 90 wheel, in which position it is caught by the shoulder on the hook 48, which is somewhat lower than the shoulder on the hook 49.

Fig. 7 shows the pin 45 just as it is starting to raise the pawl, and Fig. 8 shows the 95 position of the parts when the wheel 13 has moved one tooth forward and the pawl has been raised onto the hook 48. In this position the pin 45 lies in line with the lip 47, but a little below it. This is the form of 100 disengaging means which is operated by movement of the main wheel. The disengaging means, operated independently of the main wheel, comprises the lifting arm 54 the normal position of which is shown in 105 Fig. 1 and which is pivoted at 55. Its upward movement is preferably limited by the curved stop arm 56 which comes up under the shaft 14 carrying the wheel 13. The extremity of the lever 54 is bent upward and its tip is turned into the horizontal to form 110 a lifting finger 57 so placed that, when the lever is raised, as shown in Fig. 6, said finger raises the lip 47 up onto the shoulder of the hook 49. The lifting of the arm or 115 lever 54 may be accomplished in any desired manner, but I prefer to accomplish it automatically by means the operation of which depends upon the time during which the main operating pawl is held down in any 120 case. This preferably takes the form shown, wherein a bent gravity-lever 58, pivoted at 59 is adapted to descend against the arm 60, by depression of which the arm 54 is raised; as shown in Fig. 6. The retarding fan 61 and the train of gears 62 are connected in a well known manner to the shaft on which the arm 58 is pivoted so as to materially retard downward movement of said arm. The arm 58 is preferably connected 125 130

to said train by frictional engagement or by equivalent means permitting rapid return movement of said arm without corresponding operation of the retarding train.

5 Other retarding means may be used without departing from this invention. When the main operating lever 24 is fully raised, as in Fig. 1, the arm 58 is supported by a hook 63 carried by said lever and holding 10 said arm up against a stop 64. A padding 65 is preferably used to prevent noisy return of the arm 58.

It is obvious from the above description that when the pawl 23 and lever 24 descend 15 and reascend without pause, the slowly moving arm 58 will be caught by the hook 63 on its return movement before it has time to touch the arm 60 and operate the disengaging mechanism. On the other hand, 20 this disengaging mechanism will be operated if a sufficient pause is made while the lever 24 and pawl 23 are held down. Thus the pause made while the pawl 23 is lowered has the effect of disengaging the retaining pawl.

25 The pins 45 are so placed that each, when in the position shown in Fig. 8, and just after it has disengaged the pawl 29, stands in the path of upward movement of the lifting finger on the end of the arm 54. The 30 end of said arm is so shaped, however (see Fig. 6) that, in rising far enough to strike under a pin 45, upon a long impulse it acts like a cam upon the tripping extension 66 at the bottom extremity of the hook 48, 35 forcing said hook to the left in Figs. 1, 6, 7 and 8, and so permitting the pawl to drop back upon the wheel 13. If, on the other hand, the arm 54 is raised when no pin 45 occupies a position as shown in Fig. 8, there 40 will be nothing to impede said arm and the disengaging action above described in connection with Fig. 6 will take place. The second and higher hook 49 is necessarily utilized in this case, because the cam action of 45 the arm 54 prevents operation of the hook 48. It will thus be seen that, every time a pin 45 passes the bent tip of the pawl-finger 46, disengagement of the pawl takes place and, in order to continue uninterrupted forward movement of the wheel 13, the arm 54 must be raised to act as a restorer by its cam effect on the hook 48, before the main driving pawl 23 is raised. This is automatically accomplished in the form shown by making a 50 pause while 23 is down so as to let the retarded bar 58 come into play. At the same time, the very presence of the pin 45 prevents the bar 58 from performing its own disengaging function, by raising the member 47 onto hook 49, as in Fig. 6. Thus the 55 pin 45 is at once a disengaging and a restoring means, and the bar 58 is sometimes one and sometimes the other. That is to say, the two disengaging elements supplement 60 each other's functions as disengaging means,

and have mutual action one upon the other, as interfering means, the particular kind and relation of their activity at any given actuation of the machine being dependent upon whether the proper sort of impulse is made at the proper time, and if not so made, what sort of an impulse it is that is made out of its code relation, and what the relative positions of the disengaging means are at the time.

Assuming a wheel 13 to be supplied with a series of pins 45 substantially as shown in Figs. 1 and 3, full operation of such a wheel is produced by a succession of downward movements of the main pawl 23 which follow each other without any pause except after such movements as bring a pin 45 into the position shown in Fig. 8. Each of the last named movements must be followed by a pause long enough to permit operation of the bar 58 in releasing the pawl from the hook 48. If this is omitted the lifting of the main driving pawl 23 frees the wheel 13 entirely, and the spring 15 throws the wheel back to starting point. On the other hand, if such a pause is made at the wrong time, or when no pin 45 is in the interfering position, release of the wheel takes place as in Fig. 6. In either case the retaining pawl is freed from both hooks 48, 49 when the wheel 90 returns to normal, by impact of the tripping bar 67 on the shaft of the wheel 13 (see Figs. 2, 3 and 7). This bar strikes the tripping extensions 66 and 68 at the bottoms of the two hooks, leaving the pawl 29 in 95 its active position.

From the foregoing it will be evident that where a long impulse is given, under conditions where no pin 45 is in position, to obstruct arm 54, the retaining pawl 29 will be 100 lifted onto hook 49, and the wheel will return. Where a short impulse is given, with no pin in place, obviously the wheel will be held. Where a long impulse is given, with a pin in place, arm 54 disengages the pawl 110 from hook 48, onto which it has been moved by the pin, and the wheel will be held. Where a short impulse is given, with a pin 115 in place, the pawl 29 is disengaged, by the action of the pin upon the lip of the pawl, and the wheel returns.

I prefer to provide a safety hook 69 depending from the main operating lever and so placed as to engage under the rear edge of the side extension on the pawl 29 when this latter assumes the position shown in Fig. 6. The pivotal centers of the lever 24 and pawl 29 are so related to the form and length of the hook 69 that no engagement takes place unless in the position shown in Fig. 6. This safety hook is employed to prevent accidental failure of proper disengagement by the arm 58 due to possible careless manipulation. In order to get a "dead beat" action of the wheel 13 and in 125 130

sure its occupying the proper position at the end of each stroke I prefer to use a wedging stop or pillar 70, between which and the wheel 13 the pawl 23 forces itself at the end of each downward movement. The wheel 13 may be driven one or more teeth at a time, as long as the extent of movement is uniform. By adopting this system, all the wheels sent out for different instruments can be made exactly alike, with perforations at regular intervals for receiving pins 45. It is then only necessary to make sure that each individual instrument is supplied with pins arranged in said holes in a manner different from all other wheels in a given system. By keeping a record of the pin arrangement on each wheel, any desired instrument can be operated exclusively.

For calling telegraph operators, or wherever else a bell is to be rung the drop 21 is preferably operated as follows: A contact spring 71 is fixed behind the drop on the insulating slab 72, and plays between two contact pieces 73 and 74 which are in electric connection respectively with the springs 75 and 76. As shown diagrammatically in Fig. 9, contact of spring 71 with 74 closes circuit through the battery 77, the terminals 4 and 2 and the bell 78. This contact is produced by fall of the drop 21 the lower edge of which forces the spring 71 backward (see Fig. 5). When the drop is up, this spring makes contact with 73 and carries current from terminal 4 to terminal 3, where connection is made with the magnet 6 for working the main lever 24. In the diagram shown (which is the arrangement preferred for telegraph stations) the magnet 6 is operated by the backward movement of a relay 79 and in multiple arc with the circuit of the sounder 80, which latter circuit is also broken at 71, 73, when the bell rings. As telegraphic systems usually operate on normally closed circuit, no current passes through the magnet 6 when the line is not in use, and energy is saved.

Many of the features heretofore described may be modified and variously combined without departing from this invention. It is immaterial to the invention whether the magnet 6 acts to raise or to lower the main driving lever, and indeed the actual form described may be worked by hand or otherwise where necessary with a lock, mine 55 or other device not to be operated in connection with other instruments.

The retaining means, disengaging devices and restoring devices may all take a great variety of forms, singly or together without departing from this invention, and magnetism may be relied upon instead of mechanical means exclusively. The movement of the main machine element (whether a wheel or other device) may be used to close a circuit 60 directly, adjust the tumbler of a lock or pro-

duce any other desired result instead of making a drop fall. Many other changes and modifications may be made without departing from the scope of this invention which is not to be limited except as it is limited by the claims.

What I claim is—

1. In combination with a movable machine element, a main impelling device adapted to move said element step by step in one direction, a retaining device adapted to automatically hold said element, disengaging mechanism for said retaining device automatically actuated by movement of said element, a support for said retaining device and a movable restoring device for freeing the retaining device from said support, substantially as described. 70

2. In combination with a movable machine element, a main impelling device adapted to move said element in one direction by a series of uniform steps, a retaining device adapted to automatically hold said element, disengaging mechanism for said retaining device automatically actuated 85 when said element is moved, and a restoring device for counteracting the effect of said disengaging mechanism, substantially as described. 90

3. In combination with a movable machine element, a main impelling device adapted to move said element step by step in one direction, a retaining device adapted to automatically hold said machine element, disengaging mechanism for said retaining device automatically actuated when said element is moved, a restoring device for counteracting the effect of said disengaging mechanism and automatic retarded impelling means for said restoring means actuated 100 upon forward movement of the main impelling means, substantially as described. 105

4. In combination with a machine element adapted to be stepped, means for stepping it uniformly by each one of a series of impulses, a retaining device adapted to automatically hold said element, disengaging mechanism for said retaining device independent of said machine element, and an interfering device operated by said machine 115 element for counteracting the effect of said disengaging mechanism. 110

5. In combination with a machine element, a main impelling device adapted to move said element step by step in one direction, returning means tending to move said element in the opposite direction, a retaining device adapted to automatically engage with said element to counteract the tendency of said returning means, disengaging mechanism for said retaining device automatically actuated by movement of said element, and a restoring device for counteracting the effect of said disengaging mechanism, substantially as described. 125 130

6. In combination with a machine element, a main impelling device adapted to move said element step by step in one direction, returning means tending to move said element in the opposite direction, a retaining device adapted to automatically engage with said element to counteract the tendency of said returning means, disengaging mechanism for said retaining device automatically actuated by movement of said element, a restoring device for counteracting the effect of said disengaging mechanism and automatic retarded impelling means for said restoring device held by said impelling means and adapted to be freed by operative forward movement of the impelling means, substantially as described. 85
7. In combination with a machine element, a main reciprocating impelling device adapted to move said element step by step in one direction, constantly acting returning means tending to move said element in the opposite direction, a retaining device adapted to automatically engage with said element to counteract the tendency of said returning means, disengaging mechanism for said retaining device automatically actuated by movement of said element, and a restoring device for counteracting the effect of said disengaging mechanism, substantially as described. 90
8. In combination with a pivoted toothed sector, a main impelling pawl for moving the same in one direction, and constantly acting returning means tending to move said sector in the opposite direction, a retaining pawl adapted to automatically engage with the teeth on said sector, disengaging mechanism for said retaining pawl automatically actuated by movement of said sector and a restoring device for counteracting the effect of said disengaging mechanism, substantially as described. 95
9. In combination with a pivoted toothed sector, a main impelling pawl mounted on a pivoted lever and adapted to move said sector step by step, returning means tending to move said sector in the opposite direction, a retaining pawl engaging automatically with said sector, disengaging mechanism for said retaining pawl automatically actuated by said sector and a restoring device for counteracting the effect of said disengaging mechanism, substantially as described. 100
10. In combination with a toothed wheel, a main impelling pawl adapted to move said wheel step by step in one direction, returning means tending to move said wheel in the opposite direction, a retaining pawl engaging with said wheel, a series of pins carried by said wheel for lifting said pawl, means for holding the pawl lifted and means for returning said pawl into a position of engagement with said wheel, substantially as described. 105
11. In combination with a toothed wheel, a main impelling pawl adapted to move said wheel step by step in one direction, and returning means tending to move said wheel in the opposite direction, a retaining pawl engaging with said wheel, a series of pins carried by said wheel for lifting said pawl, a support for holding said pawl away from said wheel and means for disengaging said pawl from said support, substantially as described. 110
12. In combination with a machine element, a main impelling device adapted to move said machine element step by step in one direction, a retaining device adapted to automatically hold said machine element, disengaging mechanism for said retaining device operated by movement of said element, a support for holding said retaining device out of engagement with said element and means actuated by return of said element to its normal starting position for disconnecting said support from said retaining device, substantially as described. 115
13. In combination with a machine element, means for stepping it uniformly by each one of a series of impulses, automatic retaining means therefor, disengaging mechanism independent of said machine element and arranged to move independently of said impelling means for moving said retaining device, and an interfering device operated by movement of said machine element for preventing action of said disengaging element. 120
14. In combination with a machine element, means for stepping it uniformly by each one of a series of impulses, retaining means, disengaging means independent of said machine element and arranged to move independently of said impelling means for removing said retaining means, and a blocking device moved by said machine element into and out of the path of movement of said disengaging means. 125
15. The combination of a machine element, means for stepping it uniformly by each one of a series of impulses, a retaining means for said machine element, a lifting bar adapted to move said retaining means from said machine element, and a blocking device operated by movement of said machine element to move into and out of the path of movement of said lifting bar. 130
16. The combination with a machine element, means for stepping it uniformly by each one of a series of impulses, a retaining pawl, a lifting bar adapted to move said pawl from said machine element, and a blocking pin on said machine element for checking the movement of said lifting bar. 135
17. In combination with a main wheel, main impelling means therefor, a retaining

- 6 pawl therefor, a support for said pawl when not in operative position, a lifting bar for moving said pawl into engagement with said support, and a blocking pin on said wheel 5 for checking movement of said lifting bar, substantially as described.
18. In combination with a main wheel, main impelling means therefor, a retaining pawl therefor, a support for said pawl when not in operative position, a lifting bar for moving said pawl into engagement with said support, and a releasing device operated by return movement of said wheel for disengaging said pawl from said support, 10 substantially as described.
19. In combination with a main wheel, main impelling means therefor, a retaining pawl therefor, a support for said pawl when not in operative position, constantly acting 15 means for producing return movement of said wheel, a lifting bar for moving said pawl into engagement with said support, and a releasing device operated by return movement of said wheel for disengaging 20 said pawl from said support, substantially as described.
20. In combination with a main wheel, main impelling means therefor, a retaining pawl therefor, a support for said pawl when not in operative position, a lifting bar for moving said pawl into engagement with said support, a blocking pin on said wheel for 25 checking movement of said lifting bar and a releasing device operated by return movement of said wheel for disengaging said pawl from said support, substantially as described.
21. In combination with a main wheel, main impelling means therefor, a retaining 30 pawl therefor, a pivoted hook for supporting said pawl, constantly acting means for producing return movement of said wheel, a lifting bar for moving said pawl on to said hook, a blocking pin on said wheel for 35 checking movement of said lifting bar, and a releasing device operated by return movement of said wheel for withdrawing said hook from said pawl, substantially as described.
- 50 22. In combination with a machine element, main impelling means therefor, a retaining device therefor, disengaging mechanism independent of said machine element for removing said retaining device, an interfering device operated by movement of said machine element for preventing action of said disengaging mechanism, an automatic retarded impelling means for said disengaging mechanism, and said main impelling 55 means being adapted to effect operation of said retarded impelling means.
23. In combination with a main wheel, main impelling means therefor, a retaining 60 pawl therefor, a lifting bar adapted to remove said pawl from said wheel, a blocking device operated by movement of said wheel to move into and out of the path of movement of said lifting bar, automatic retarded impelling means for said lifting bar, and said main impelling means, being adapted 65 to effect operation of said retarded impelling means.
24. In combination with a main wheel, main impelling means therefor, a retaining pawl therefor, a lifting bar adapted to remove said pawl from said wheel, a pin on said main wheel to check movement of said lifting bar, and an automatic retarded impelling means for said lifting bar, said main impelling means being adapted to effect the 70 operation of said retarded means, substantially as described.
25. In combination with a main wheel, main impelling means therefor, a retaining pawl therefor, a lifting bar adapted to remove said pawl from said wheel, a hook for supporting said pawl when removed, a pin on said wheel for checking movement of said lifting bar, automatic retarded impelling 75 means for said lifting bar, and a releasing device operated by return movement of said wheel for disengaging said hook from said pawl, substantially as described.
26. A machine element, a retaining device therefor, a disengaging mechanism for said retaining device operated by movement of said machine element, a second disengaging mechanism independent of said machine element, and separate means for restoring said retaining means to normal, substantially as described.
27. A machine element, a retaining device therefor, a disengaging mechanism for said retaining device independent of said machine element, and a second disengaging mechanism operated by movement of said machine element, and adapted in a certain position to block operative movement of said first named disengaging mechanism, substantially as described.
28. A machine element, a retaining device therefor, a disengaging mechanism for said retaining device operated by movement of said machine element, and a second disengaging mechanism independent of said machine element and adapted to counteract the effect of said first named disengaging mechanism, substantially as described.
29. A main wheel, a retaining pawl therefor, a pin projecting from one face of said wheel so as to lift said pawl when brought in proper position, a hook for holding said pawl when lifted and a pivoted cam lever adapted to remove said hook from said pawl, substantially as described.
30. A main wheel, a retaining pawl there-

- for, a pivoted lifting bar adapted to remove said pawl from said wheel, a hook for holding said pawl when lifted and a pin projecting from said wheel and adapted when in one position to block the operation of said lifting bar, substantially as described. 5
31. A main wheel, a retaining pawl therefor, a pivoted lifting bar adapted to remove said pawl from said wheel, a hook for holding said pawl when lifted, a pin projecting from one face of said wheel, and adapted when in one position to block the operation of said lifting bar, and a releasing bar on the shaft of said wheel adapted to separate said hook and pawl when the wheel is returned to a starting position, substantially as described. 10
32. A main wheel, a retaining pawl therefor, an upper and a lower support for receiving said pawl when removed from said wheel, a lifting bar and cam lever combined adapted when operated to raise said pawl to said upper support while removing said lower support, and a pin projecting from one face of said wheel so as to block said lifting bar in one position and to lift said pawl on to the lower support just before reaching said position, substantially as described. 15
33. A main wheel, a retaining pawl, and two disengaging mechanisms for said pawl each of which acts in one position to counteract the effect of the other, substantially as described. 20
34. A main wheel, a retaining pawl, a disengaging mechanism for said pawl operated by said main wheel and a second disengaging mechanism independent of said wheel, substantially as described. 25
35. A main wheel, a retaining pawl therefor, an upper and a lower pivoted pawl-supporting hook, a lever carrying a lifting bar adapted to raise said pawl to said upper hook, a cam for tripping said lower hook, and a pin on said wheel for raising said pawl to said lower hook and for blocking said lifting bar in one position of said pin, substantially as described. 30
36. A main wheel, a retaining pawl therefor, an upper and a lower hook pivoted separately and each adapted to receive said pawl, disengaging mechanism for placing said pawl on said lower hook, and separate disengaging mechanism for placing said pawl on said upper hook, substantially as described. 35
37. A main wheel, a retaining pawl therefor, an upper and a lower hook pivoted separately and each adapted to receive said pawl, disengaging mechanism operated by said main wheel for placing said pawl on said lower hook, and a second disengaging mechanism independent of said main wheel for placing said pawl on said upper hook, substantially as described. 40
38. A main wheel, a retaining pawl therefor, an upper and a lower hook pivoted separately, and each adapted to receive said pawl, a pin on said main wheel for placing said pawl on said lower hook, and a pivoted lifting bar for placing said pawl on said upper hook, substantially as described. 45
39. A main wheel, a retaining pawl therefor, an upper and a lower hook pivoted separately and each adapted to receive said pawl, a lifting bar in position such as to place said pawl on said upper hook and a pin on said main wheel in position such as to place said pawl on said lower hook and acting in one position to block the movement of said lifting bar, substantially as described. 50
40. A main wheel, a retaining pawl therefor, an upper and a lower hook pivoted separately and each adapted to receive said pawl, a pin on said main wheel in position such as to place said pawl on said lower hook, a pivoted lifting bar for placing said pawl on said upper hook, and releasing mechanism operated by return movement of said wheel to trip both of said hooks, substantially as described. 55
41. A main wheel, a main impelling lever and pawl attached thereto for driving said wheel, a retaining pawl, disengaging means for said pawl, and a safety hook on said impelling lever for catching said pawl when lifted from said wheel, substantially as described. 60
42. In a selective mechanical operator, in combination a main wheel, impelling means therefor adapted to propel said wheel by a series of uniform steps, automatic means for returning said wheel to its normal starting position, a retaining pawl, a disengaging means for said pawl retarded with respect to movement of said impelling means and pins on said wheel adapted to move into and out of the path of said disengaging means, substantially as described. 65
43. In a selective mechanical operator in combination, a main wheel, impelling means therefor adapted to propel said wheel by a series of uniform steps, automatic means for returning said wheel to its normal starting position, a retaining pawl, a swinging hook for said pawl, a retarded disengaging means adapted to make contact with said hook to swing the same and pins on said wheel adapted to move into and out of the path of said disengaging means, substantially as described. 70
44. In a selective mechanical operator in combination, a main wheel, impelling means therefor adapted to propel said wheel by a series of uniform steps, automatic means for returning said wheel to its normal starting position, a retaining pawl, two swinging hooks for said pawl at different levels, a retarded disengaging means adapted to raise said pawl and swing one of said hooks and 75

pins on said wheel adapted to move into and out of the path of said disengaging means, substantially as described.

45. In a selective mechanical operator, in combination a main toothed wheel, a retaining pawl therefor, and a series of pins projecting from one face of said wheel for raising said pawl, substantially as described. 70

46. In combination with the other mechanical elements of a selective mechanical operator, a main toothed wheel, provided with a series of pins projecting from the same and a retaining pawl for said wheel bent at its end to form a sloping lip in the path of movement of said pins substantially as described. 10

47. In combination with the other mechanical elements of a selective mechanical operator, a main toothed wheel provided with a series of pins projecting from the same, a swinging hook and a retaining pawl bent at its end to form a sloping lip in the path of said pins and having a lateral projection adapted to rest on said hook when said pawl 20 is raised, substantially as described. 25

48. In combination with the other mechanical elements of a selective mechanical operator, a main toothed wheel provided with a series of pins projecting from the same, a swinging hook and a retaining pawl having a lateral projection a portion of which projects into the path of movement of said pins and another portion of which embraces said hook and is adapted to rest on the same 30 when the pawl is raised, substantially as described. 35

49. In a selective mechanical operator, a main toothed wheel, a retaining pawl having an engaging lip, and two pivotally carried supports of different heights adapted to engage said lip, substantially as described. 40

50. In a selective mechanical operator, a main toothed wheel carrying a pin, a retaining pawl having an engaging lip, and a downward projection adapted to be struck by said pin, and a pivoted hook adapted to engage with said lip when said pawl is lifted, substantially as described. 45

51. In a selective mechanical operator, a main wheel, retaining means therefor, disengaging mechanism for said retaining means, a pivoted lever adapted to operate said disengaging mechanism and a train of wheels and retarding fan attached to said lever, substantially as described. 50

52. In combination with a machine element, means for driving said element in one direction a uniform distance for each impulse on the main line, means for retaining said element against retrogression, an automatic disengaging device for said latter means arranged to move independently of said driving means, and mechanism for preventing operation of said disengaging device. 60

53. In a device of the class described, a toothed wheel, a retaining pawl therefor, a holding device for said pawl, a retarded means for disengaging said holding device from the pawl, impelling means for said wheel and means connected to said impelling means for restraining said retarded means when said impelling means are inactive, substantially as described. 70

54. In an apparatus of the class described, in combination, a machine element, means for stepping it uniformly by each one of a codally arranged series of impulses of different characteristics, means for causing the return of the machine element to normal by an impulse of one characteristic out of its codal relation, and means for causing the return of the machine element to normal by an impulse of different characteristic out of its codal relation. 75 80

55. In apparatus of the kind described, in combination, a machine element, means for stepping it uniformly by each one of a codally arranged series of impulses of different characteristics, retaining means, means adapted to affect the retaining means and cause the return of said member by an impulse of one characteristic out of its codal relation, and other means adapted to affect the retaining means and cause the return 90 of said member by an impulse of another characteristic out of its codal relation. 95

56. In apparatus of the kind described, in combination, a machine element, means for stepping it by each one of a codally arranged series of impulses of different characteristics, means for effecting the return of said member to normal by an impulse of given characteristic out of its codal relation, and other means for effecting the return of the member to normal upon an impulse of a given different characteristic out of its codal relation, one of said means adapted to negative the effect of the other when the impulse is of a certain characteristic. 100 105

57. In apparatus of the kind described, in combination, a machine element, means for stepping it by each one of a codally arranged series of impulses of different characteristics, means for causing the return of said member to normal upon an impulse of given characteristic out of its codal relation, and other means for causing the return of the member to normal upon an impulse of a given different characteristic out of its codal relation, one of said means adapted to negative the effect of the other when they occupy certain positions. 110 115

58. In apparatus of the kind described, in combination, a machine element, means for stepping it by each one of a codally arranged series of impulses of different characteristics, means for effecting the return of said member to normal upon an impulse of given characteristic out of its codal rela- 120 125 130

- tion, and other means for effecting the return of the member to normal upon an impulse of a given different characteristic out of its codal relation one of said means 5 adapted to negative the effect of the other when they occupy certain positions and when the impulse is of a certain characteristic.
59. In apparatus of the kind described, in combination, a machine element, means adapted to step the same forward uniformly by a codally arranged series of impulses of different characteristics, a retaining means, means for disengaging said retaining means 10 upon an impulse of given characteristic out of its proper-codal relation, and other means for disengaging said retaining means upon an impulse of different characteristic out of its codal relation.
60. In apparatus of the kind described, in combination, a machine element, means for stepping the same forward by a codally arranged series of impulses of different characteristics, retaining means, means for dis- 15 engaging said retaining means upon an impulse of given characteristic out of its codal relation, and other means for disengaging said retaining means upon an impulse of different characteristic out of its codal relation, one of said last named means adapt- 20 ed to negative the effect of the other when the impulse is of a given characteristic.
61. In apparatus of the kind described, in combination, a machine element, means for stepping it forward by each one of a codally arranged series of impulses of different characteristics, retaining means, means for disengaging said retaining means upon an impulse of any characteristic, and means 25 adapted to negative the effect of said last named means when said impulse is of a given characteristic.
62. In apparatus of the kind described, in combination, a machine element, means for stepping the same forward by each one of a codally arranged series of impulses of different characteristics, retaining means, means for disengaging said retaining means upon an impulse of any characteristic, and 30 means controlled by a long impulse adapted to negative the effect of said last-named means.
63. In apparatus of the kind described, in combination, a machine element, means for moving the same forward by each one of a codally arranged series of impulses of different characteristics, retaining means, means including a lever for disengaging said retaining means upon a long impulse, and 35 means controlled by an impulse adapted to negative the effect of said last named means when said impulse is made in its codal relation.
64. In apparatus of the kind described, 40 in combination, a machine element, means for stepping the same forward uniformly by each one of a codally arranged series of impulses of different characteristics, retaining means, and a plurality of means for disengaging said retaining means, one of said means being operable upon an impulse of one characteristic, and another upon an impulse of another characteristic.
65. In apparatus of the kind described, in combination, a machine element, means for stepping the same forward uniformly by each one of a series of codally arranged impulses of different characteristics, retaining means, and a plurality of means for disengaging said retaining means, one of said 45 means being operable upon an impulse of any characteristic and the other upon an impulse of a certain characteristic.
66. In an apparatus of the kind described, in combination, a machine element, means for stepping said element forward uniformly by a codally arranged series of impulses of different characteristics, retaining means for said machine element, a plurality 50 of members movable for disengaging said retaining means, said members having mutual interfering action upon each other, the effective operation of either of said members being dependent upon the position of the machine element and upon the character of 55 the next preceding impulse.
67. In apparatus of the kind described, in combination, a machine element, impulse means for stepping the same, a retaining member, means upon the machine element 60 for moving said retaining member from engagement with the stepped member, means adapted to negative the effect of said element and to cause engagement of the retaining member with the stepped member when the 65 said means upon the machine element occupies a given position and upon an impulse of given characteristic.
68. In apparatus of the kind described, in combination, a machine element adapted 70 to be stepped, impulse means for stepping the same, a retaining member, means upon the machine element for moving the retaining member from engagement with the stepped member, and means adapted to nega- 75 tive the effect of said element and to cause engagement of the retaining member with the stepped member when the said means upon the machine element occupies a given position and upon an impulse of given char- 80 acteristic.
69. In apparatus of the kind described, in combination, a machine element adapted to be stepped, impulse means for stepping the same, a retaining member, means upon the machine element for moving said retaining member from engagement with the stepped member, a retarded means adapted to nega- 85 tive the effect of said means on the machine element and to cause engagement of the re- 90

taining member with the machine element when the said means upon the machine element occupies a given position and upon an impulse of given characteristic.

- 5 70. In apparatus of the kind described, in combination, a machine element, means for stepping the same, a retaining member, means for moving said retaining member from engagement with the stepped member, 10 and means adapted to negative the effect of said last named means and to cause engagement of the retaining member with the stepped member when the said disengaging means occupies a given position and upon 15 an impulse of given characteristic.

71. In apparatus of the kind described, in combination, a member adapted to be stepped from a normal initial position, impulse means for stepping said member, means for 20 retaining said member against retrograde movement comprising a relatively movable holding member engaging said stepped member, means upon the stepped member adapted to move the holding member from engagement with the stepped member, means 25 for holding said retaining member momentarily in a position of disengagement from the stepped member, and retarded means adapted to coöperate with the second mentioned holding means to free the retaining member, whereby it may reengage the 30 stepped member and hold it, the operation of the retarded member upon the second mentioned holding member being determined by the characteristic of the impulse. 35

72. In an apparatus of the class described, in combination, a machine element, means for stepping it uniformly by each one of a codally arranged series of impulses of different characteristics, means for effecting 40 the return of the machine element to normal upon an impulse of one characteristic out of its codal relation, and means effecting the return of the machine element to normal upon 45 an impulse of different characteristic out of its codal relation, one of said means being controlled by the machine element.

73. In apparatus of the kind described, in combination, a machine element, means 50 for stepping it by each one of a codally arranged series of impulses of different characteristics, retaining means, means adapted to affect the retaining means and permit the return of said element upon an impulse of one characteristic out of its codal relation, and other means adapted to affect the retaining means and permit the return of said element upon an impulse of another characteristic out of its codal relation, one of said 55 means being controlled by the machine element.

74. In apparatus of the kind described, in combination, a machine element, means for stepping it by each one of a codally ar-

ranged series of impulses of different characteristics, means effecting the return of said member to normal upon an impulse of given characteristic out of its codal relation, and other means effecting the return of the member to normal upon an impulse of given characteristic out of its codal relation, one of said means adapted to negative the effect of the other when the impulse is of a predetermined characteristic, one of said means being controlled by the machine element. 75

75. In apparatus of the kind described, in combination, a machine element, means for stepping it by each one of a codally arranged series of impulses of different characteristics, means for effecting the return 80 of said element to normal upon an impulse of given characteristic out of its codal relation, and other means for effecting the return of the element to normal upon an impulse of given characteristic out of its codal relation, one of said means adapted to negative the effect of the other when they occupy certain positions, one of said means being controlled by the machine element.

76. In apparatus of the kind described, 90 in combination, a machine element, means for stepping it by each one of a codally arranged series of impulses of different characteristics, means for effecting the return of said element to normal upon an impulse of 95 given characteristic out of its codal relation, and other means permitting the return of the element to normal upon an impulse of given characteristic out of its codal relation, one of said means adapted to negative the effect of the other when they occupy predetermined positions and when the impulse is of a certain characteristic, one of said means being controlled by the machine element. 100

77. In apparatus of the kind described, 105 in combination, a machine element, means adapted to step the same forward uniformly by a codally arranged series of impulses of different characteristics, a retaining means, means for disengaging said retaining means 110 upon an impulse of given characteristic out of its proper codal relation, and other means for disengaging said retaining means upon an impulse of different characteristic out of its codal relation, one of said means being controlled by the machine element. 115

78. In apparatus of the kind described, in combination, a machine element, means for stepping the same forward by a codally arranged series of impulses of different 120 characteristics, retaining means, means for disengaging said retaining means upon an impulse of given characteristic out of its codal relation, and other means for disengaging said retaining means upon an impulse of different characteristic out of its codal relation, one of said last named means adapted to negative the effect of the other. 125

when the impulse is of a given characteristic, one of said means being controlled by the machine element.

79. In apparatus of the kind described, in combination, a machine element, means for stepping it forward by each one of a codally arranged series of impulses of different characteristics, retaining means, means for disengaging said retaining means upon an impulse of any characteristic out of its codal relation, and means adapted to negative the effect of said last named means when said impulse is of a given characteristic, one of said means being controlled by the machine element.

80. In apparatus of the kind described, in combination, a machine element, means for stepping the same forward by each one of a codally arranged series of impulses of different characteristics, retaining means, means for disengaging said retaining means upon an impulse of any characteristic, and means adapted to negative the effect of said last named means when said impulse is long, one of said means being controlled by the machine element.

81. In apparatus of the kind described, in combination, a machine element, means for moving the same forward by each one of a codally arranged series of impulses of different characteristics, retaining means, means for disengaging said retaining means upon a long impulse, and means adapted to negative the effect of said last named means when said impulse is made in its codal relation, one of said means being controlled by the machine element.

82. In apparatus of the kind described, in combination, a machine element, means for stepping the same forward uniformly by each one of a codally arranged series of different characteristics, retaining means, and a plurality of means for disengaging said retaining means, one of said means being operable upon an impulse of one characteristic, and another upon an impulse of another characteristic, one of said means being controlled by the machine element.

83. In apparatus of the kind described, in combination, a machine element, means for stepping the same forward uniformly by each one of a series of codally arranged impulses of different characteristics, retaining means, and a plurality of means for disengaging said retaining means, one of said means being operable upon an impulse of any characteristic and the other upon an impulse of a certain characteristic, one of said means being controlled by the machine element.

84. In apparatus of the kind described, in combination, a machine element, means for stepping the same forward by a codally arranged series of impulses of different characteristics, retaining means, a plurality of

movable means for disengaging said retaining means, said last named means adapted to have a mutual interfering action upon each other, the effective operation of either of said means being dependent upon the position of the machine element and upon the character of the next preceding impulse, one of said means being controlled by the machine element.

85. In apparatus of the class described, in combination, a machine element, means for stepping it uniformly by each one of a codally arranged series of impulses of different characteristics, means for effecting the return of the machine element to normal upon an impulse of one characteristic out of its codal relation, and means effecting the return of the machine element to normal upon an impulse of different characteristic out of its codal relation, one of said means being controlled by the stepping means.

86. In apparatus of the kind described, in combination, a machine element, means for stepping it uniformly by each one of a codally arranged series of impulses of different characteristics, retaining means, means adapted to affect the retaining means and cause the return of said element upon an impulse of one characteristic out of its codal relation, and other means adapted to affect the retaining means and cause the return of said element upon an impulse of another characteristic out of its codal relation, one of said means being controlled by the stepping means.

87. In apparatus of the kind described, in combination, a machine element, means for stepping it by each one of a codally arranged series of impulses of different characteristics, means effecting the return of said element to normal upon an impulse of given characteristic out of its codal relation, and other means effecting the return of the element to normal upon an impulse of a given different characteristic out of its codal relation, one of said means adapted to negative the effect of the other when the impulse is of a certain characteristic, one of said means being controlled by the stepping means.

88. In apparatus of the kind described, in combination, a machine element, means for stepping it by each one of a codally arranged series of impulses of different characteristics, means effecting the return of said element to normal upon an impulse of given characteristic out of its codal relation, and other means effecting the return of the element to normal upon an impulse of a given different characteristic out of its codal relation, one of said means adapted to negative the effect of the other when they occupy certain positions, one of said means being controlled by the stepping means.

89. In apparatus of the kind described, in

combination, a machine element, means for stepping it by each one of a codally arranged series of impulses of different characteristics, means effecting the return of 5 said element to normal upon an impulse of given characteristic out of its codal relation, and other means effecting the return of the element to normal upon an impulse of a given different characteristic out of 10 its codal relation, one of said means adapted to negative the effect of the other when they occupy certain positions and when the impulse is of a certain characteristic, one of said means being controlled by the stepping 15 means.

90. In apparatus of the kind described, in combination, a machine element, means adapted to step the same forward uniformly by a codally arranged series of impulses 20 of different characteristics, retaining means, means for disengaging said retaining means upon an impulse of given characteristic out of its proper codal relation, and other means for disengaging said retaining means upon 25 an impulse of different characteristic out of its codal relation, one of said means being controlled by the stepping means.

91. In apparatus of the kind described, in combination, a machine element, means 30 for stepping the same forward by a codally arranged series of impulses of different characteristics, retaining means, means for disengaging said retaining means upon an impulse of given characteristic out of its 35 codal relation, and other means for disengaging said retaining means upon an impulse of different characteristic out of its codal relation, one of said last named means adapted to negative the effect of the other 40 when the impulse is of a given characteristic, one of said means being controlled by the stepping means.

92. In apparatus of the kind described, in combination, a machine element, means for 45 stepping it forward by each one of a codally arranged series of impulses of different characteristics, retaining means, means for disengaging said retaining means upon an impulse of any characteristic, and means adapted 50 to negative the effect of said last named means when said impulse is of a given characteristic, one of said means being controlled by the stepping means.

93. In apparatus of the kind described, in 55 combination, a machine element, means for stepping the same forward by each one of a codally arranged series of impulses of different characteristics, retaining means, means for disengaging said retaining means 60 upon an impulse of any characteristic, and means adapted to negative the effect of said last named means when said impulse is long, one of said means being controlled by the stepping means.

65 94. In apparatus of the kind described, in

combination, a machine element, means for moving the same forward by each one of a codally arranged series of impulses of different characteristics, retaining means, means for disengaging said retaining means upon a 70 long impulse, and means adapted to negative the effect of said last named means when said impulse is made in its codal relation, one of said means being controlled by the stepping means. 75

95. In apparatus of the kind described, in combination, a machine element, means for stepping the same forward uniformly by each one of a codally arranged series of impulses of different characteristics, retaining 80 means, and a plurality of means for disengaging said retaining means, one of said means being operable upon an impulse of one characteristic, and another upon an impulse of another characteristic, one of said 85 means being controlled by the stepping means.

96. In apparatus of the kind described, in combination, a machine element, means for stepping the same forward uniformly by 90 each one of a series of codally arranged impulses of different characteristics, retaining means, and a plurality of means for disengaging said retaining means, one of said means being operable upon an impulse of 95 any characteristic and the other upon an impulse of a certain characteristic, one of said means being controlled by the stepping means.

97. In apparatus of the kind described, in combination, a machine element, means for stepping the same forward by a codally arranged series of impulses of different characteristics, retaining means, a plurality of 100 movable means for disengaging said retaining means, said last named means adapted to have mutual interfering action upon each other, and the disengaging or interfering action of said means being determined by their relative movements and the character of the 110 impulse upon which said movement takes place, one of said means being controlled by the stepping means. 105

98. In an apparatus of the class described, in combination, a machine element, means 115 for stepping it uniformly by each one of a codally arranged series of impulses of different characteristics, means for effecting the return of the machine element to normal upon an impulse of one characteristic out of 120 its codal relation, and means effecting the return of the machine element to normal upon an impulse of different characteristic out of its codal relation, one of said means being controlled by the machine element, the 125 other by the stepping means.

99. In apparatus of the kind described, in combination, a machine element, means for stepping it uniformly by each one of a codally arranged series of impulses of differ- 130

ent characteristics, retaining means, means adapted to affect the retaining means to permit the return of said member upon an impulse of one characteristic out of its codal relation, 5 and other means adapted to affect the retaining means to permit the return of said member upon an impulse of another characteristic out of its codal relation, one of said means being controlled by the machine element, the 10 other by the stepping means.

100. In apparatus of the kind described, in combination, a machine element, means for stepping it by each one of a codally arranged series of impulses of different characteristics, means effecting the return of said element to normal upon an impulse or given characteristic out of its codal relation, and other means effecting the return of the element to normal upon an impulse of a given 15 different characteristic out of its codal relation, one of said means adapted to negative the effect of the other when the impulse is of a certain characteristic, one of said means being controlled by the machine element, 20 the other by the stepping means.

101. In apparatus of the kind described, in combination, a machine element, means for stepping it by each one of a codally arranged series of impulses of different characteristics, means effecting the return of said element to normal upon an impulse of given 25 characteristic out of its codal relation, and other means effecting the return of the element to normal upon an impulse of a given different characteristic out of its codal relation, one of said means adapted to negative the effect of the other when they occupy certain positions, one of said means being controlled by the machine element, the other 30 by the stepping means.

102. In apparatus of the kind described, in combination, a machine element, means for stepping it by each one of a codally arranged series of impulses of different characteristics, means effecting the return of said element to normal upon an impulse of given 45 characteristic out of its codal relation, and other means effecting the return of the element to normal upon an impulse of a given different characteristic out of its codal relation, one of said means adapted to negative the effect of the other when they occupy certain positions and when the impulse is of a certain characteristic, one of said means being controlled by the machine element, the other 50 by the stepping means.

103. In apparatus of the kind described, in combination, a machine element, means adapted to step the same forward by a codally arranged series of impulses of different characteristics, retaining means, means for disengaging said retaining means upon an impulse of given characteristic out of its proper codal relation, and other means 55 for disengaging said retaining means

upon an impulse of different characteristic out of its codal relation, one of said means being controlled by the machine element, the other by the stepping means.

104. In apparatus of the kind described, in combination, a machine element, means for stepping the same forward by a codally arranged series of impulses of different characteristics, retaining means, means for disengaging said retaining means upon an impulse of given characteristic out of its codal relation, and other means for disengaging said retaining means upon an 70 impulse of different characteristic out of its codal relation, one of said last named means 75 adapted to negative the effect of the other when the impulse is of a given characteristic, one of said means being controlled by the machine element, the other by the stepping means.

105. In apparatus of the kind described, in combination, a machine element, means for stepping it forward by each one of a codally arranged series of impulses of different characteristics, retaining means, means for 80 disengaging said retaining means upon an impulse of any characteristic, and means adapted to negative the effect of said last named means when said impulse is of a given characteristic, one of said means being 85 controlled by the machine element, the other by the stepping means.

106. In apparatus of the kind described, in combination, a machine element, means for stepping the same forward by each one 100 of a codally arranged series of impulses of different characteristics, retaining means, means for disengaging said retaining means upon an impulse of any characteristic, and means adapted to negative the effect of said 105 last named means when said impulse is long, one of said means being controlled by the machine element, the other by the stepping means.

107. In apparatus of the kind described, 110 in combination, a machine element, means for moving the same forward by each one of a codally arranged series of impulses of different characteristics, retaining means, means for disengaging said retaining means 115 upon a long impulse, and means adapted to negative the effect of said last named means when said impulse is made in its codal relation, one of said means being controlled by the machine element, the other by the stepping means.

108. In apparatus of the kind described, in combination, a machine element, means for stepping the same forward by each one 120 of a codally arranged series of impulses of different characteristics, a retaining means, and a plurality of means for disengaging said retaining means, one of said means being operable upon an impulse of one characteristic, and another upon an impulse 125

of another characteristic, one of said means being controlled by the machine element, the other by the stepping means.

109. In apparatus of the kind described, 5 in combination, a machine element, means for stepping the same forward by each one of a series of codally arranged impulses of different characteristics, a retaining means, and a plurality of means for disengaging 10 said retaining means, one of said means being operable upon an impulse of any characteristic and the other upon an impulse of a certain characteristic, one of said means being controlled by the machine element, the 15 other by the stepping means.

110. In apparatus of the kind described, in combination, a machine element, means

for stepping the same forward by a codally arranged series of impulses of different characteristics, retaining means, a plurality 20 of movable means for disengaging said retaining means, said last named means adapted to have mutual interfering action upon each other, and the disengaging or interfering action of said means being determined 25 by their relative movements and the character of the impulse upon which said movement takes place, one of said means being controlled by the machine element, the other by the stepping means.
